UNITED STATES PATENT OFFICE.

JOHN H. BURKHOLDER, OF ASHLAND, OHIO, ASSIGNOR TO ELITE MANUFACTURING COMPANY, OF ASHLAND, OHIO, A PARTNERSHIP.

LIFTING-JACK.

No. 874,904.

Specification of Letters Patent.

Patented Dec. 24, 1907.

Application filed June 10, 1907. Serial No. 378,130.

To all whom it may concern:

Be it known that I, JOHN H. BURKHOLDER, a citizen of the United States, residing at Ashland, in the county of Ashland and State of Ohio, have invented certain new and useful Improvements in Lifting-Jacks, and do declare that the following is a full, clear, and exact description of the invention, which will enable others skilled in the art to which it appertains to make and use the same.

My invention relates to lifting jacks, and the invention consists in a lifting jack of compound construction, whereby a continuous operation of the jack is sustained in either direction according as it is set for movement of the lift upward or downward, all substantially as shown and described and particularly pointed out in the claims.

20 In the accompanying drawings, Figure 1 is a side elevation of the jack partially broken away at the bottom, and Fig. 2 is a vertical sectional elevation on line 2—2, Fig. 1. Fig. 3 is a cross section on line 25 3—3, Fig. 1, and Fig. 4 is a sectional elevation on line 4—4, Fig. 1.

This device comprises a dual or compound construction of jack, in which one side or part of the power applying mechanism supplements the other side or part in immediate succession, so as to maintain a continuous movement of the lift member upward or downward according to its adjustments for the time being and whereby 35 the speed of operation is doubled over a single acting machine, as will now more clearly appear. Thus, having reference to the drawings, the device comprises a single tubular standard A and a lift member B movable up 40 and down in said standard. Said member B is screw threaded substantially its entire length from its lower end upward and has a guide b at its lower end running in channels or grooves in said standard, whereby it is held to a direct up and down movement and prevented from turning in the standard. A preferably rotatable head 2 is fixed 45 on lift member B, and a miter gear C is supported in a recess or open space in the top of the standard between arms 3 which support the extremity of the standard above said recess and gear. Said gear is threaded internally like a nut and engages

threaded lift B, to raise and lower the same according to direction of its rotation. 55

Operation of miter gear C, and through it the raising of lift member B, is effected by means of two bevel gears D and E, respectively, supported oppositely on standard A on suitable pivot or screw pins or shafts 4 60 removably threaded into said standard and serving also as pivot supports for handle or lever extensions 6 on lever G. Said extensions project inward from head 7 of said lever and engage on said pins inside of gears 65 D and E, and pawls 9 and 10 are pivoted in said head and are double acting and adapted to throw either end into working engagement with the corresponding gear according as said gear is to be turned one way or the 70 other. Furthermore, said pawls are operatively mounted in the ends of head 7 on the ends of a rod or shaft 12 diagonally disposed in said head and engaged centrally with a spring pressed bolt 13 adapted to rotate in 75 its bearings in handle G and to hold said pawls in engaging relation whichever ends may be thrown forward for the time being, and opposite ends of said pawls work at the same time, relatively as seen in Fig. 1. 80 Hence both gears D and E act together successively when lever G is operated up and down at its free end, and cause gear C to rotate continuously in one direction until the parts are reversed. In this operation 85 first one pawl will act and then the other, and the pawl idle for the moment will slide over the cogs of its wheel till the direction of handle G is reversed when it will act and the other will be idle and slide. Thus one pawl 90 acts on the down stroke of the handle and the other on the up stroke, making a continuous rotation of gear C, and the direction of rotation of said gear is changed when the positions of said pawls is reversed, throwing 95 their other ends into engagement. This is done by pressing the thumb against the upper disengaged end of the pawl, whichever it may be, when both pawls will be reversed through their connection 12. Said pawls 100 have ears 14 behind their pivots 15 through which connecting rod 12 engages, and spring 17 about bolt 13 normally presses upon said rod 12 and therethrough against ears 14 to hold both pawls in operative engagement 105 with their respective gears in either of the

reversible positions of the pawls. To this end it will be noted that bolt 13 is both free to work and slide and is located axially on a central line passing through the lever and 5 pawl pivots.

What I claim is:—

In lifting jacks, a standard A, a lift member B therein and a rotatable actuating gear C screwed onto said lift member and seated 10 in the upper end of said standard, gears E rotatably mounted on opposite sides of said standard adapted to rotate in opposite directions and meshing with said actuating gear, an operating handle G having a cross 15 head and a substantially yoke shaped extension 6 therefor supported on opposite sides of standard A, and double engaging pawls 9 and 10 pivoted between said cross-head and extension 6 and adapted to engage

20 said side gears at one or the other end according to their position, a connecting rod 12 between said pawls, a bolt 13 socketed in the base of said cross head and having said rod 12 extending through the same, a spring 17 about said bolt and pressing against said rod 25 12, and pawls having extensions outside their pivots engaged by said rod, whereby said pawls are jointly thrown into raising and lowering engagement for said lift member and held by a torsional action of said 30 spring.

In testimony whereof I sign this specification in the presence of two witnesses.

JOHN H. BURKHOLDER.
